ARTIFICIAL LIMB CONSTRUCTION

John H. F. Stewart, Mount Clemens, Mich.

Application October 8, 1948, Serial No. 53,435

3 Claims. (Cl. 3-3)

1

This invention relates to artificial body members and particularly to an improved artificial leg.

The invention is more particularly concerned with a leg construction in which the structural members are particularly adapted to cooperate with a hydraulic or mechanical unit for controlling the action of the joints and which provides not only a rugged reliable construction, but one which is of pleasing appearance and may be serviced or repaired with ease.

The invention also deals with a leg construction which is particularly adapted for quantity production while at the same time permitting of custom fitting by artisans skilled in that work, and permitting the use of conventional methods for such fitting and conventional materials for those parts of the leg which require it.

More particularly, it is an object of the invention to provide an artificial leg having a rigid exterior contour which closely simulates the natural leg contour and permits full free action at the joints while maintaining a continuous smooth exterior surface in all positions to which the joint may be bent. Specifically, it is an object to provide a construction wherein a rigid structure is provided for each of the three leg members having clearance space at the joints to permit joint action, and to provide a flexible elastic covering continuously extending over the three leg members and smoothly bridging the gaps between them at all joint positions.

A further object of the invention is to provide a construction for the intermediate or shin member which allows adequate room for a mechanical hydraulic or other type of joint controlling unit in a completely concealed position, and which is at the same time readily made accessible for service or replacement. More specifically, it is an object to provide a leg member having a frame designed for handling the necessary loads with the minimum weight and providing adequate space for the control unit together with a rigid contoured tubular covering for concealing the frame and unit, giving proper shape to the leg member, and which may be readily removed for access to the unit.

It is a further object of the invention to provide a leg member having a load bearing frame which is resilient to endwise compressive forces for the purpose of facilitating leg action.

A further object of the invention is to provide a leg construction, particularly one having a joint control unit in which the more expensive parts may be manufactured in large quantities at re-

2

duced cost, and yet which will permit each leg to be individually fitted to the user by the use of conventional methods and materials. More specifically, it is an object to provide a construction comprising a sub-assembly which includes the shin and ankle joints complete together with the lower portion of the thigh member and the upper portion of the foot member properly contoured to cooperate with the shin member, and which may be later provided with a custom fitted socket and a custom fitted foot, the contours of which may be smoothly paired to the thigh and foot portions.

Further objects and advantages of the present invention will be apparent from the following description, reference being had to the accompanying drawings wherein a preferred form of the present invention is clearly shown.

In the drawings:

20 Figure 1 is a side view of an artificial leg embodying a preferred form of the present invention showing the knee bent.

Figure 2 is a view corresponding to Figure 1 showing the knee straight.

25 Figure 3 is a fragmentary sectional view on line 3-3 of Figure 1.

Figure 4 is an exploded view of a sub-assembly forming part of the leg illustrated in Figure 1.

Figure 5 is a detail view of a control cable coupling.

Figure 6 is a side view partly in section of the leg shown in Figure 1.

Figure 7 is a partial sectional view taken on line 7-7 of Figure 6.

35 Figure 8 is a fragmentary sectional view taken on line 8-8 of Figure 6.

Figure 9 is a fragmentary rear view of the lower portion of the thigh member with the knee joint removed.

40 Referring now to Figure 1 there is shown a leg having a thigh member 10, a shin member 12, and a foot member 14 which are articulated by means of a knee joint 16 and an ankle joint 18. The foot member may also have a toe joint as indicated at 20.

45 As shown more particularly in Figures 6 and 7, the shin member is provided with a main frame 22 preferably formed of two welded tubular truss members 24 and 26 having pivot journals at their upper and lower ends. The truss members are joined at their upper end by a U-shaped crossbar 28 and are joined at a point below their center by a cross tube 30. Mounted on a pivot at 32 is a hydraulic control unit generally designated 34 having a knee piston rod 36 at its upper end and

an ankle piston rod 38 at its lower end. The unit illustrated is of the type disclosed more fully in my Patent 2,478,721, granted August 9, 1949, although it will be understood that other types of control units may be utilized including those which control only the knee.

The foot member 14 is pivotally secured to the lower end of the frame 22 by a pivot pin 40 extending between the upstanding flanges 42 of a foot attaching piece 44. The latter may also have a pin 46 to receive a connecting rod 48 pivoted to the ankle piston rod 38. The attaching piece 44 is provided with a cylindrical boss 50 and a cylindrical key 52 which may receive screws 54 by which the foot member 56 is attached. The foot member carries a cuff 58 rigidly secured thereto and extending upwardly to cover most of the ankle joint. The cuff 58 serves not only as a covering but also as a form or guide to which the foot member 56 may be conformed or faired in smoothly when the latter is manufactured. The cuff is preferably a sheet metal stamping of aluminum or magnesium.

Pivoted to the upper end of the frame 22 is a knee bracket 60 having depending ears 62 and 64. The former receive a pin 66 forming the main knee pivot and the latter receive a pivot 68 directly connected to the knee piston rod 36. The bracket 60 may be secured to a base plate 70 forming the base of the thigh socket 10. A reinforcing bracket 72 is also preferably provided together with a depending knee cap member 74 rigidly secured to the plate 70. Securely attached to the upper part of the base plate 70 is a tubular socket 76 which may be custom fitted to the stump of the user. The socket 76 may be recessed as shown at 78 in Figure 3 to receive remote control cables 80 which connect between a manual control assembly 82 secured to the side of the socket, and the lower control cable sections 84 which connect with the control unit 34. Suitable separable couplings 86, as shown in Figure 5, are provided at the rear of the knee cap to permit disassembly of the thigh member 10 from the shin member 12. In order to facilitate such disassembly, while maintaining a permanent rigid attachment of the socket 76 to the base plate 70, the knee bracket 60 may be attached by screws 88 and 90. The former screws are received in special screw sockets 92, as shown in Figure 8, which permanently attach the reinforcing plate 72 to the base plate 70.

In order to provide a pleasing appearance to the exterior of the leg and to reasonably simulate the appearance of the natural leg, while at the same time permitting a full range of bending of the knee and ankle joints, certain special provisions are made as follows: The shin member 12 is provided with a rigid tubular shell 92 which is shaped in general to simulate a natural shin. The shell 92 may be formed of sheet metal, plastic, or other similar light weight rigid materials. It is formed preferably as a continuous tube which may be slipped over the frame from the bottom when the foot 56 is removed from its attaching piece 42. The shell 92 may be secured to the cross piece 28 by screws, as illustrated, and also anchored to the frame adjacent the cross tube 30. The upper front face of the shell 92 extends upwardly substantially above the knee pivot 66 and its upper edge lies forward of the knee pivot by substantially the same amount. In other words, as viewed in Figure 6, the upper edge of the shin face lies at a point which is on a line about 45° above the horizontal passing

through the axis 66. The depending knee cap member 74 has its front face curved into a convex shape, the curvature of which as viewed in Figure 6 is approximately along a circular arc centered on the pivot 66 in the quadrant just below horizontal. The lower edge of the knee cap lies closely adjacent to the shin facing when the knee is straight and at a point which is on a line passing through pivot 66 about 45° below the horizontal. Thus, when the knee is bent substantially 90° the tip of the knee cap member 74 lies just forward of the upper edge of the front shin facing.

The upper rear part of the shell 92 is cut away as indicated at 94 so that the lower rear portion of the thigh socket 76 may be received therein to permit bending the knee to an acute angle. Also for this purpose the rear face of the socket 76 is provided with two vertical recesses 96 which receive the side edges of the shell 92 adjacent the opening 94. These recesses may be somewhat wider than necessary to merely receive the shell edges in order to assure freedom from pinching the elastic covering later to be described. The lower end of the shell 92 may be curved upwardly at its front and rear portions to permit swinging of the ankle joint without interference with the cuff 58.

This construction of the rigid exterior parts of the leg adjacent the joints provides a minimum of clearance space at these points. In order to provide a complete continuous smooth contour for appearance purposes and to completely enclose the working parts and the joints, the three rigid members of the leg are covered with a flexible elastic tubular sheet covering as illustrated in Figures 1 and 2 at 98. This covering may be of various materials and one suitable type comprises an elastic surgical stocking of knit fabric which is stretched tautly over the leg and bridges the clearance spaces at the joints 16 and 18. In order to avoid depressions at the ankle and on the front part of the knee joint, this covering and the surface of the rigid members are chosen to have a low frictional coefficient so that the covering 98 may readily slide upon the surface of the members 10, 12, and 14. This sliding action takes place along a zone adjacent each of the joints while the joints are bending, and permits the covering 98 to be maintained taut to bridge the clearance spaces adjacent the joint and provide a smooth continuous contour to the leg as a whole. The covering 98 may, if desired, be dipped or sprayed with latex or similar plastic waterproof material in order to make the leg water and dust tight, or the covering may be formed of continuous elastic film having elastic characteristics. The interior surface of the covering may be provided with a lubricant such as a film of grease or talc.

In order to facilitate manufacture of the leg and custom fitting in widely distributed localities, the leg is so constructed that the entire shin section and knee and ankle joints may be manufactured in subassembly form by quantity production methods. As shown in Figure 4, such a subassembly may comprise a complete shin section 12, including all the knee and ankle joint parts, together with a socket attaching piece comprising the base plate 70, reinforcing plate 72, and the knee cap 74. At its opposite end the subassembly may be furnished with the foot attaching piece 42, screws 54, and the cuff 58. Along with these may be furnished the control assembly 82 and its associated cables 80. Such

a subassembly may be manufactured in large lots in a few standard shin lengths and calf diameters. It may then be provided with a custom fitted socket and foot made locally in the conventional manner by a custom limb maker. The socket and foot parts are readily fitted to the contour of the attaching pieces furnished with the subassembly by any artisans skilled in this work using conventional materials, methods, and tools. At the same time the provision of the knee cap piece and the ankle cuff provide the necessary contours adjacent the knee and ankle joints to insure proper action of the elastic covering.

The tubular frame 24 is preferably given an outwardly bowed form as shown clearly in Figure 7 and is thereby made somewhat resilient to take up shock and compression in an endwise direction which aids materially to the ease in use of the leg. The frame is also somewhat torsionally resilient about the longitudinal axis of the leg to ease twisting strains between the socket and stump of the user.

Another feature of the present construction resides in the foot attaching piece 42 which is of metal and especially formed so as to provide a reliable attachment to the footpiece 56 which may be made of wood or similar material. By the use of the large cylindrical boss 50 together with the flange at the upper end thereof, a relatively large bearing area between the metal and wooden parts is obtained and this together with the cylindrical key 52 has been found to reliably secure the foot member to its attaching piece without loosening during long periods of use.

It will thus be seen that the present invention provides an improved artificial leg construction which is not only rugged and reliable but pleasing in appearance, easily serviced, and readily adapted to manufacture and fitting at low cost.

While the form of embodiment of the invention as herein disclosed constitutes a preferred form, it is to be understood that other forms might be adopted, all coming within the scope of the claims which follow.

What is claimed is as follows:

1. In an artificial leg having a thigh socket member, a shin member and a foot member pivotally connected together, the combination of a load bearing frame connecting the knee and ankle

50

pivots, a pivot actuating and control unit carried by the frame, said frame comprising a pair of side frames secured to each other adjacent the pivots in spaced relation and having oppositely bowed portions resiliently deformable under endwise load whereby the shin member may be elastically compressed a substantial amount by the weight of the user.

2. In an artificial leg having a thigh socket member, a shin member and a foot member pivotally connected together, the combination of a load bearing frame connecting the knee and ankle pivots, a pivot actuating and control unit carried by the frame, said frame comprising a pair of welded tube, truss-like, side frames secured to each other adjacent the pivots in spaced relation and having oppositely bowed portions resiliently deformable under endwise load whereby the shin member may be elastically compressed a substantial amount by the weight of the user.

10 15 20 25 30 35 40 45 50

3. In an artificial leg having a thigh socket member, a shin member and a foot member pivotally connected together, the combination of a load bearing frame connecting the knee and ankle pivots, a pivot actuating and control unit carried by the frame and a tubular shell covering the frame and unit, said frame being elastically compressible in an endwise direction under the weight of the user, and said shell having its ends spaced from the thigh and foot members to permit such compression.

JOHN H. F. STEWART.
